UNITED STATES PATENT OFFICE.

RALPH H. SCHWARTZ, OF BAKERSFIELD, CALIFORNIA.

PARCEL-HOLDING ATTACHMENT FOR AUTOMOBILES AND THE LIKE.

1,185,548.

Specification of Letters Patent.

Patented May 30, 1916.

Application filed July 10, 1915. Serial No. 39,075.

To all whom it may concern:

Be it known that I, RALPH H. SCHWARTZ, a citizen of the United States, residing at Bakersfield, in the county of Kern and State of California, have invented a new and useful Parcel-Holding Attachment for Automobiles and the like, of which the following is a specification.

- This invention relates to a parcel holding attachment especially designed for use upon the running board of an automobile and in like places, one of the objects of the invention being to provide a device of this character which can be applied readily to a running board and which can be quickly fastened thereto so as to be held against accidental displacement, said attachment being adjustable to tightly engage parcels of different sizes.
- Another object is to provide an attachment of this character which is cheap to manufacture and which does not detract from the appearance of the vehicle to which it is applied.
- With the foregoing and other objects in view which will appear as the description proceeds, the invention resides in the combination and arrangement of parts and in the details of construction hereinafter described and claimed, it being understood that changes in the precise embodiment of the invention herein disclosed, can be made within the scope of what is claimed, without departing from the spirit of the invention.
- In the accompanying drawings the preferred form of the invention has been shown. In said drawings: Figure 1 is a front elevation of the parcel holding attachment, the same being shown in position for use, a portion of the running board engaged thereby being shown in section. Fig. 2 is a vertical section through portions of the attachment. Fig. 3 is a section on line A—B Fig. 1. Fig. 4 is a plan view of a clip used in connection with the apparatus.

Referring to the figures by characters of reference 1 designates a base strip having a longitudinal slot 2 and upstanding from the outer end of this base strip is a post 3 slidably engaged by split sleeves 4 formed upon upper and lower tubular arms 5 and 6 respectively. These split sleeves are adapted to be adjusted along the post 3 and to be clamped theron by means of screws 7 so as to remain fixed relative to the post. Slid-

ably mounted in the arm 5 is a rod 8 having a depending finger 9 at its free end, while slidably mounted in the arm 6 is a rod 10 having an upstanding finger 11 preferably provided with a ring 12. Set screws 13 are provided in the two arms for holding the rods 8 and 10 against movement relative to the arms. A snap hook 13' may be connected adjustably to the upper end portion of the post 3, this snap hook engaging a sleeve 14 which is adapted to be secured at any point desired on the post. Fitted within the slot 2 is a clamping block 15 having a depending ear 16 to which is secured one end of a cam lever 17. This cam lever is fulcrumed in a yoke 18 which straddles and is pivotally connected to the sides of the strip 1. The cam lever 17 is so constructed that when it is swung upwardly against the bottom of the strip 1, its point of connection with the ear 16 will move past the dead center and thus not only elevate the block 15 relative to the strip 1, but hold said block in raised position.

In using the device the strip 1 is placed under the running board X of the vehicle and the arm 6 is adjusted downwardly so as to rest upon the running board. Lever 17 is then swung outwardly and upwardly against the base strip 1 so as to thrust upwardly against block 15 and cause said block to press tightly against the bottom face of the running board so as to clamp the running board against the arm 6. The parcel to be secured is placed above the arm 6 and the rod 10 can be adjusted longitudinally so as to bring the finger 11 close to the inner side of the parcel. Arm 5 is then adjusted downwardly onto the parcel and its rod 8 is also adjusted longitudinally. If desired a strip can be attached to the ring 12 and be detachably engaged by the hook 13'. It is to be understood that one or more of the devices herein described can be arranged on a running board and that when the same is in position it will not detract from the appearance of the vehicle to which it is attached. Furthermore it will constitute an efficient means for securing parcels to the running board so that their loss while in transit will be prevented. The entire attachment can be quickly removed from the running board simply by lowering the handle portion of the cam lever 17 so as thus to lower the block 15 out of engagement.

with the running board. The attachment can then be slid outwardly off of the running board as will be obvious. If desired, and as shown in Fig. 1, the clip 19 may be 5 adjustably mounted on the post 3, the same being utilized for the purpose of engaging a canteen, water bag or the like suspended from the snap hook 13'.
What is claimed is:—

- 10 1. A parcel holding attachment for running boards and the like, including a base strip, a post upstanding therefrom, upper and lower parcel engaging arms adjustable along the post, and means movably mounted relative to the base strip for binding one of the arms against the running board.
- 15 2. A parcel holding attachment for running boards and the like, including a slotted base strip, a post upstanding therefrom, upper and lower parcel engaging arms adjustable along the post, and means movably mounted within the slot in the base strip for binding one of the arms against the running board.
- 20 3. A parcel holding attachment for running boards and the like, including a base, a clamping block adjustably mounted in the base, a post upstanding from the base, arms independently adjustable along the post for 25 engaging a parcel, and means for shifting the clamping block relative to the base to clamp

a running board between said block and one of the arms.

4. A parcel holding attachment for running boards and the like, including a base, 35 a clamping block movably mounted therein, a post upstanding from the base, telescopic arms adjustably connected to the post, and means for shifting the clamping block relative to the base to grip a running board between said block and one of the arms.

5. A parcel holding attachment for running boards and the like, including a base, 45 a clamping block movably mounted therein, a post upstanding from the base, telescopic arms adjustably connected to the post, and means for shifting the clamping block relative to the base to grip a running board between said block and one of the arms, said means including a yoke pivotally 50 connected to and depending from the base and a cam lever fulcrumed upon the yoke and pivotally connected to the block, said lever and yoke coöperating to hold the block in clamping position.

In testimony that I claim the foregoing as my own, I have hereto affixed my signature in the presence of two witnesses.

RALPH H. SCHWARTZ.
